UNITED STATES PATENT OFFICE.

JOHN G. BANJOCK, OF ZEHNER, PENNSYLVANIA.

AUTOMATIC VALVE.

No. 894,102.

Specification of Letters Patent.

Patented July 21, 1908.

Application filed March 25, 1907. Serial No. 364,463.

To all whom it may concern:

Be it known that I, JOHN G. BANJOCK, a citizen of United States, residing at Zehner, in the county of Luzerne, State of Pennsylvania, have invented certain new and useful Improvements in Automatic Valves; and I do hereby declare the following to be a full, clear, and exact description of the invention, such as will enable others skilled in the art to which it appertains to make and use the same.

This invention has relation to so-called automatic or self-operating steam-valves.

It is the object of the invention to provide a valve of the kind mentioned that may be so arranged as to govern the energy with which the blower for the fire in a steam-engine operates to keep the heat, or fire, and consequently the steam generated, at a regular predetermined degree, the said valve and blower virtually taking the place of the usual steam-governor for controlling the speed of the engine, incidentally to the performance of its other functions.

The nature of the invention is ascertainable from the degree of novelty portrayed in the annexed drawings, forming a part of this specification, in view of which it will first be described in detail with respect to its construction and mode of operation and then be pointed out with particularity in the subjoined claims.

Of the said drawings—Figure 1 is a front view. Fig. 2 is a side view. Fig. 3 is a sectional view taken in the plane 3 3, Fig. 2. Fig. 4 is a transverse section on line 4 4, of Fig. 1. Fig. 5 is a vertical elevation similar to Fig. 3, but showing a modified form of the device.

Similar numerals of reference designate similar parts or features, as the case may be, wherever they occur.

While in the following specification my invention will be described as applied to steam-engines for the purpose of regulating the energy or speed with which a blower of a steam-boiler may be operated, it will appear obvious that the improvements may be employed for any other purpose, to regulate steam pressure or indicate the variations in speed pressure in a boiler.

In the drawings, having reference first to Figs. 1 to 4, inclusive, 10 designates the shell provided with hollow horizontal extensions 11 and 12 interiorly screwthreaded for the reception of pipes, said extensions forming inlet and outlet passages or ports, respec-

tively, for steam from the boiler. The shell is provided with a vertical opening, 13, through it, joining the inlet and outlet ports at a point between the same. The bottom portions of the vertical opening is provided with a valve seat, 14, and is closed at its extreme lower end by a plug, 15. In the upper portion of the vertical opening there is a valve, 16, having a vertical stem, 17, by means of which it may be raised and lowered to limit the extent or area of the passage 18, which joins the inlet and outlet ports, or close it entirely.

19 designates a steam cylinder provided with a piston chamber, 20, at its upper end and having its lower end extended and connected with the upper extensions, 21, of a connecting plate, 22, the lower extension, 23, of which has a screw-threaded connection 75 with the casing, 10. The piston chamber 20 is divided from the lower part of the cylinder 19 by a partition, 24, which is provided with a stuffing-box, 26, through which, and through a stuffing-box 27, in the partition 80 plate 22, the stem 17 of the valve 16 extends in its projection into the steam-chamber 20.

27 designates a regularly-packed piston secured on the upper end of the valve-stem 17, and having a steam-tight fit in the steam-chamber 20.

25 designates a spring interposed between the bottom of the piston 27 and the bottom of the chamber 20, and operating to press the piston 27 upward, carrying the valve 90 16 with it and thus opening the passage 18 between the inlet and outlet ports 11 and 12 from the steam-boiler, (not shown).

29 designates a steam-pipe leading from the inlet 11 up to and over the top of the 95 chamber 20 which it enters at the center of its covered top 30. The pipe 29 is provided with a valve, 31, of ordinary construction, which controls the volume of steam entering the chamber 20 above the piston 27.

Under the construction thus far described it will be understood that the steam passing from the steam-boiler through the ports 11 and 12 and intermediate passage way 18 will be conducted to the engine that operates the 105 blower for the fire of the main engine, and that the amount of steam passing through to the blower-operating means will depend upon the extent of the opening of the passage 18 between the ports 11 and 12. Moreover, 110 it will be understood that the area or extent of the port 18 will depend upon the position

of the valve 16. If said valve is raised to its fullest extent the passage 18 will be opened to its full extent and consequently the maximum amount of steam will be admitted through the ports 11 and 12. On the other hand if the valve should be nearly closed down to its seat 14 but little steam will be admitted through said ports; and if said valve should be fully closed upon its seat 14 the steam will be shut off entirely from passing through the port 11 and 12, and consequently the blower will cease to be operated.

The valve 12 is regulated as to its position by the degree of pressure of the steam admitted to the chamber 20 of the cylinder 19 through the pipe 29. If said pipe is fully opened the steam entering the port 11 will pass up through the pipe 29, and into the chamber 20 depressing the piston 27' and valve stem 17, the extent of which depression will depend of course upon the pressure of the steam in the said chamber 20.

When the steam is low in the boiler of course the pressure upon the piston 27 in the chamber 20 will be lighter than when the steam is at a higher pressure in the boiler, and hence there will be less pressure on the top of the piston 27 and the valve 16 will be raised by the action of the spring 25, opening the passage 18 between the ports 11 and 12 and leaving therethrough a larger volume of steam to operate the blower at a more rapid rate so as to bring up the fire and consequently the steam in the boiler. As the latter rises the pressure in the chamber 20 will be increased and the valve 16 operated to gradually shut off the degree of steam passing through the passage 18 until, it may be, the said passage is entirely closed. In this way it will be noted that the device shown and described will automatically operate to regulate the pressure of steam in the boiler and through the regulation of the energy with which the blower is operated consequently the invention may take the place of an ordinary governor for a steam engine.

It is to be understood, of course, that in the explanation of the foregoing mode of operation of the invention, it is to be kept in mind that the area of pressure on the bottom of the valve 16 is less than on the top of the piston 27 to depress it.

In Fig. 5 I have shown a different form of the invention, but in which the general principle remains the same. In said view the pipe 29 extends vertically up from the pipe 11' leading from the steam-boiler into the inlet 11 of the casing 10. The said pipe 29 enters the steam-chamber 20 of the steam cylinder 19 at its outer end, the said cylinder being arranged in a horizontal instead of a vertical position. The piston 27 is arranged in the cylinder with the spring 25 in its opposite end and acting between the spring and the outer end of its chamber. In this case

the piston stem *a* extends through a stuffing box in the inner end of the cylinder, and is constructed as a rack *b* supported to slide in the upper end of an upright, *c*, and is in engagement with an elongated gear *d* on the stem 17 of the valve 16. The said valve-stem is provided with an external screw-thread *e* which engages an internal screw-thread in the partition-plate 22, so that as the piston 27 is moved in the cylinder 19 it will screw the valve 16 up and down toward its seat 14 which is arranged in a partition *f* in the passage 18 connecting the ports 11 and 12 and regulate the extent of said passage as before described, for the same purpose. A hand-wheel *g* is secured on the upper end of the valve-stem 17 for operating the valve 16 by hand when desired, and a brace *n* extends up from the casing 10 to assist with the pipe 29 in supporting the steam-cylinder 19.

In Fig. 6 the pipe 29 is shown as extending vertically up from the inlet port 11 and as entering the steam-cylinder below the piston 27' and operates on the said valve to press it upward in the chamber 20. Instead of employing a spring, 25, to press the valve down against the pressure of the steam below it, the valve 16 is extended as at *i* and is provided with a lateral passageway *j* through it. To the lower end of the extension *i* of the valve there is a stem *k* connected with its lower end to hold the piston 27 against the operation of the steam on the piston in substantially the same manner as the spring.

The foregoing modifications show the changes that may be made in the mere-form and arrangement of parts without departing from the nature or spirit of the invention.

What is claimed is—

An automatic valve comprising a main casing having an inlet opening and outlet opening and a bore at right angles to the axes of the said openings, said bore opening through the bottom and top of the casing, a cylinder imposed upon the casing with its bore in axial alinement with the bore of the casing, said inlet and outlet openings having a connecting passage intersecting the bore of the casing, a valve disposed in the bore of the casing and movable into and out of position to close said passage, a piston in the cylinder, a rod common to and connecting the piston and valve, a spring disposed to hold the piston yieldingly with the valve in open position, a by-pass connecting the inlet opening of the casing with the end of the cylinder and a plug removably engaged in the lower end of the bore of the casing.

In testimony whereof, I affix my signature, in presence of two witnesses.

JOHN G. BANJOCK.
